(57) **CLAIM**

The ornamental design for a holster holder device, as shown and described.

DESCRIPTION

FIG. 1 is a front perspective view of a holster holder device showing our new design;

FIG. 2 is a front elevation view of our holster holder device of FIG. 1;

FIG. 3 is a rear elevation view of our holster holder device of FIG. 1;

FIG. 4 is a top plan view of our holster holder device of FIG. 1;

FIG. 5 is a bottom plan view of our holster holder device of FIG. 1;

FIG. 6 is a side elevation view of our holster device of FIG. 1; and,

FIG. 7 is a rear elevation view of our holster holder device of FIG. 1, it being understood that the broken line disclosure of an attached holster is for illustrative purposes only and forms no part of the claimed design.
